ASSIGNORS TO COMMERCIAL WIRELESS AND DEVELOPMENT CO., OF SAN FRAN-
CISCO, CALIFORNIA, A CORPORATION OF ARIZONA.

SOUND-MAGNIFYING PHONOGRAPH.

1,329,928.

Specification of Letters Patent.

Patented Feb. 3, 1920.

Application filed July 3, 1916. Serial No. 107,442.

To all whom it may concern:

Be it known that we, EDWIN STEWART PRIDHAM and PETER LAURITS JENSEN, citizens of the United States, residing at Napa, in the county of Napa and State of California, have invented new and useful Improvements in Sound-Magnifying Phonographs, of which the following is a specification.

This invention relates to phonographs and has for its object to provide a loud speaking phonograph, wherein means are provided for modulating the tones whereby to secure any desired volume of sound.

The invention relates to an entirely new machine or sound magnifying phonograph, suitable for reproducing sound records in large halls, auditoriums and amphitheaters and before out-of-door gatherings or wherever manifestly the ordinary talking machine would be inaudible and futile. These results are accomplished through the combination with the ordinary sound box of a talking machine, of a microphone transmitter and a sound amplifier with or without means for varying the volume of sound given out by the amplifier; the sound varying means however, being capable of use with the ordinary talking machine.

One form which our invention may assume is exemplified in the following description and illustrated in the accompanying drawings in which—

Figure 1 shows a vertical sectional view of a phonograph embodying our invention.

Fig. 2 shows a plan view of the same.

Fig. 3 shows a fragmentary view of the side of the cabinet illustrating the control means for the electrical connections.

Fig. 4 shows a side elevation of the amplifying receiver employed in our device.

Fig. 5 shows a horizontal sectional view of the device.

Fig. 6 shows a side elevation of the controlling mechanism employed herein.

Fig. 7 shows a diagram of the electrical connections.

Figs. 8 and 9 show plan views of the multi-contact controlling switch employed herein.

Fig. 10 shows a vertical longitudinal sectional view of the amplifying receiver.

In the drawings we have shown a specially designed phonograph cabinet 10, wherein the usual amplifier is removed, but obviously

the ordinary phonograph cabinet may be used and our invention applied thereto as an attachment. We connect a microphone transmitter 11 to the goose-neck 12 or other conduit communicating with the ordinary traveling sound box or reproducer 13 of a phonograph; the swinging arm 14, corresponding to the usual sound conducting arm of a phonograph, being out of communication with the goose-neck and sound box. From the microphone, current carrying wires 15 extend to a sound amplifying receiver 16, preferably located within the cabinet of the phonograph.

In general, the sound amplifying receiver comprises a conducting coil 17, for carrying the modulated currents, and which is rigidly attached to a receiver diaphragm 18. This coil is disposed at right angles to the lines of force of a magnetic field created by a magnet 19 energized by coils 20. A current passing through the conducting coil caused by the sound waves will cut transversely the lines of force of the magnetic field with the result that a reaction takes place which vibrates the coil and actuates the diaphragm. The strength of these vibrations being a product of three factors, viz., length of the conductor exposed to the lines of force, strength of the magnetic field and strength of the current passing through the conductor, by increasing the length of the conductor acted upon by the lines of force and using a strong magnetic force, a great increase in vibration is secured although the current strength in the conducting coil may be comparatively weak. The vibrations of the conducting coil are transmitted directly to the diaphragm and accurately reproduce the sound waves in greatly augmented volume. In fact, the sounds from an ordinary phonograph equipped with our invention, have been heard at a distance as great as three miles. The musical value of these sounds is in no way impaired by this great amplification, but on the contrary, an improvement is noted. Mechanical amplification of sound destroys the wave lengths and is conductive of harshness and blatancy, whereas, electric amplification preserves the wave lengths and produces full and rounded tones with a consequent rendering of values otherwise lost.

Mounted upon the receiver in direct com-

munication with the diaphragm thereof, is an amplifying horn 21, also within the cabinet.

- In order that we may dispense with separate dry-cells and utilize the regular 110 volt direct current service for operating this device, we introduce a storage battery 22 in the transmitter circuit and connect the amplifying receiver and the storage battery to the service mains, the connections being so arranged that the storage battery will be recharged automatically. The circuits are as illustrated in Fig. 7. In this arrangement there is shown a feed circuit comprising mains 23 and 24, the former of which indicates the positive lead and is connected through a suitable resistance coil 25, with the energizing coils 20 of the magnetic circuit of the amplifying receiver. From the coils 20, the current passes to a four-pole snap-switch 26, the contacts of which are marked A, B, C and D respectively. The closing and opening of the switch is performed by the rotation of a metallic cross 27. For clearness, we have shown the switch in Figs. 8 and 9 as having one-eighth of a turn, with the contacts all in the same plane, but in practice these switches are given one-fourth of a turn and adjacent contacts are in different planes. When the switch is closed, all contacts are in metallic connection with each other, thus providing an arrangement for divided circuits, the purpose of which will be made apparent hereinafter.
- The first circuit may be called the energizing and charging circuit and is as follows: Current from the lead 23 flows through the resistance coil 25 to the magnetic coils 20, thence to the contact A of the switch 26 and through the metallic cross arms 27 to the contact D. From contact D a connection leads to the positive pole of the storage battery 22, and the negative pole of the storage battery is connected to the negative lead 24 of the feed circuit. The resistance coil 25, combined with the resistance of the energizing coils 20 should be of such value that the storage battery will receive its normal charging current.
- A second circuit controlled by the switch 26 is the transmitter circuit. In this connection we find it desirable to introduce a talking transmitter 28 in addition to the phonographic transmitter 11, so arranged that either may be cut in independently, whereby oral announcements, speeches, etc., may be made through the amplifying receiver and the horn between musical renditions. Such an arrangement is exceptionally desirable for public entertainments.
- Both transmitters have a common wire running to the negative pole of the storage battery and separate wires running to contacts 29 and 30 respectively, of a switch 31.
- The arm of the switch 31 is connected

through a variable resistance coil 32 to one terminal of the primary of an induction coil 33. The other terminal of the primary is connected to the switch contact B. The secondary of the coil 33 is connected to the 70 vibrating coil 17 of the amplifying receiver.

The circuit just described is as follows: Current from the positive terminal of the storage battery flows to the contact D, through the switch arm 27 to contact B, 75 thence to the primary of the induction coil 33 and from the primary to the variable resistance 32. From the resistance coil the circuit leads to the arm of the switch 31, where the circuit may be completed either 80 through transmitter 11 or 28, to the negative terminal of the storage battery. The secondary of the induction coil communicates the modulated currents to the movable coil of the receiver.

A third circuit controlled by the switch 26 may be termed the indicator circuit and comprises a signal lamp 34 connected to the switch point C at one side and to the positive lead 23 at the other side. Current from the contact C passes through the signal light to the positive side of the outside circuit. This signal light serves a very useful purpose in that it indicates that the energizing current is charging the storage battery, and 90 is a visible signal warning the operator to turn the current off when not using the instrument. It is also of use in showing whether the charging current is connected to the proper terminals of the battery, for 100 if the charging current be in series with the battery or the voltage of the battery be added to that of the charging current, the light will glow with increased brightness, while if the terminals are properly connected, the voltage of the charging current less 105 the battery voltage will be the voltage of the lamp circuit and therefore the lamp will glow less brightly.

By introducing more or less resistance into 110 the transmitter circuit and thereby varying the strength of the current passing through the vibrating coil 17, we are enabled to control the volume of sound delivered by the horn, whereby to produce loud, medium, or 115 soft tones, as desired. As shown in Fig. 6, the variable resistance is controlled by a rheostat arm 35 and comprises a series of conducting brackets 36 projecting out from a base-board 37, secured to the interior of the 120 cabinet. These brackets are arranged in an arc about the rheostat arm and each carries a binding post 38 at its opposite ends and has a contact point 39 at its inner end projecting into the path of the rheostat arm. 125 Between the outer end of each bracket and the inner end of the adjacent bracket is a small resistance coil 40, thus putting all of the brackets and coils in electrical connection with each other. One end of the arc is 130

provided with a conductor plate 41, to which the end of the adjacent resistance coil is connected and this plate also has a contact for engagement with the rheostat arm and is connected by a wire 42 with the arm of the switch 31. The rheostat arm 35 is connected to the primary of the induction coil 33, and thereby any desired number of resistance coils may be included in the transmitter circuit by manipulating the rheostat arm. The base-board 37, as shown in Figs. 5 and 6 is carried within the cabinet 10 and has mounted upon it, in addition to the variable resistance coils, the switches 26 and 31, the lamp 34 and the induction coil 33. Exterior controlling means are provided for each of the parts, as shown in Fig. 3, comprising a knob 43, for the switch 26, having pointers 44 movable into juxtaposition with the indicating devices marked "Off" and "On." A knob 45 operates the arm of the switch 31 and carries a pointer 46 to register with the indicating devices marked "T" and "M," indicating the adjustments for the talking and music transmitters. An aperture 47 is provided in the switch board and cabinet to permit the signal lamp 34 to be seen. The rheostat arm 35 is operated by a knob 48 which carries a pointer 49, the limits of movement of which are marked "L" and "S" for loud or soft playing.

An important feature of the switch 26 is the contact B which controls the transmitter circuit. It was discovered in our early work with this switch that upon breaking the contacts all at the same time, a high voltage discharge took place around the transmitter circuit, due to the sudden breaking of the current through the energizing coils of the magnet. As this current was opposed by the storage battery current in the charging direction, but added to it through the transmitter circuit, it will be seen that of the two circuits which could absorb this high voltage, the transmitter circuit took the greater portion of it and this invariably led to the puncturing of the transmitters. To obviate this difficulty the contact point B is made much shorter than the others so that when the metallic arms 27 are rotated to break the contacts, the transmitter circuit will be broken before the others, and in this way all danger of puncturing the transmitters is obviated.

It will be noted that by the use of the storage battery, it is possible for us to use the regular 110 volt direct current service with exceptionally good results. The battery is charged with a current slightly in excess of the value used in the transmitter, thus keeping the battery in a fully charged condition at all times. Also the battery acts as an exceedingly low resistance path for the fluctuating transmitter currents in the transmitter circuit.

The variable resistance which is placed in the transmitter circuit is of great value as a modulator, especially when phonographic music is being reproduced. By means of the rheostat arm, the current may be weakened or strengthened at will, thus easily controlling the volume of the reproduction.

While we have shown and described herein but one form of device, it will be understood nevertheless, that our invention is susceptible of modification, and therefore many changes in the construction and arrangement of the several parts may be employed, without departing from the spirit of the invention as disclosed in the appended claims.

Having thus described our invention, what we claim and desire to secure by Letters Patent is—

1. In an instrument for amplifying sounds, including a transmitter, a receiver, a signal lamp and a storage battery, circuits for said transmitter, receiver, signal lamp and storage battery, a multi-point switch for controlling said circuits, said switch being so constructed as to break said transmitter circuit in advance of said other circuits.

2. In a phonograph, the combination with a record and its reproducer of a microphone transmitter connected with the reproducer, a receiver for said transmitter, said receiver having its field produced by an electromagnet, electrical means in connection with said transmitter and receiver for amplifying sounds, and an electrical circuit, said circuit being adapted to be connected to a commercial direct current supply service, said circuit including a resistance, the energizing coils of the electromagnet of the receiver, and a storage battery in series with said coils and resistance whereby said storage battery receives its proper charging current from the commercial source.

3. In a phonograph, the combination with a record and its reproducer, of a transmitter in connection with said reproducer, a receiver for said transmitter, electrical means in connection with said transmitter and receiver for amplifying sounds affecting said transmitter, electric circuits, said circuits comprising a charging circuit connected to a commercial supply source, said charging circuit including the energizing coils of said receiver, a resistance and a storage battery, a transmitter circuit operated by said storage battery, a signal circuit including a lamp, all of said circuits being interconnected by means of a multi-point switch for the control of said circuits, substantially as shown.

4. In a phonograph, the combination with a record and its reproducer of a microphone transmitter connected with the reproducer, a receiver for said transmitter, electrical

- means in connection with said receiver for amplifying the sound waves and electrical connections for the transmitter and receiver, said connections including a receiving circuit connected with the service mains, a storage battery in said receiving circuit to receive a charging current therefrom, a transmitter circuit operated by said storage battery and a multi-contact switch for controlling said circuits and putting them all in electrical connection with each other, said switch being operable to break the transmitter circuit in advance of the receiving and charging circuit.
- 15 5. In a phonograph, the combination with a record and its reproducer of a microphone transmitter connected with the reproducer, a receiver for said transmitter, electrical means in connection with said receiver for amplifying the sound waves and electrical connections for the transmitter and receiver, said connections including a receiving circuit connected with the service mains, a storage battery in said receiving circuit to receive a charging current therefrom, a transmitter circuit operated by said storage battery and a multi-contact switch for controlling said circuits and putting them all in electrical connection with each other and an indicator circuit connected with said switch and with the positive lead of the service mains.
6. In a phonograph, the combination with a record and its reproducer of a microphone transmitter connected with the reproducer, a receiver for said transmitter and electromagnetic means in connection with said receiver for amplifying the sound waves, said means comprising a conducting coil for the modulated currents secured to the diaphragm of the receiver, an electromagnet for producing lines of force at right angles to the coil, whereby to cause said coil to vibrate the diaphragm, and actuating circuits for said transmitter and receiver, comprising connections between the service mains and the amplifying means, a storage battery included in said connections to receive a charging current from the service mains and connections between the storage battery and the transmitter for operating the latter, said last named connections including an induction coil having its primary in circuit with the transmitter and its secondary in circuit with the coil on the receiver diaphragm and a variable resistance coil in said transmitter circuit for varying the strength of the current waves whereby to modulate the sounds.
- 60 7. In a phonograph, the combination with a cabinet, a record and a reproducing device of a microphone transmitter connected with the reproducer, an amplifying receiver carried within the cabinet and connected electrically with the transmitter, an amplifying horn on the receiver also contained within the cabinet, a variable resistance device carried within the cabinet and connected with the transmitter circuit for varying the strength of the current waves, and means operable from the exterior of the cabinet for controlling said variable resistance device.
8. In a phonograph, the combination with a cabinet, a record and a reproducing device of a microphone transmitter connected with the reproducer, an amplifying receiver carried within the cabinet and connected electrically with the transmitter, an amplifying horn on the receiver also contained within the cabinet, a talking transmitter adapted to be connected with the receiver and means operable from the exterior of the cabinet for cutting the talking and phonographic transmitters into circuit with the receiver independently.
9. In a phonograph, the combination with a cabinet, a record and a reproducing device of a microphone transmitter connected with the reproducer, an amplifying receiver carried within the cabinet and connected electrically with the transmitter, an amplifying horn on the receiver also contained within the cabinet, actuating means for the transmitter and amplifying receiver, comprising a receiving circuit connected with an outside supply circuit, a storage battery within the cabinet and connected with the receiving circuit, whereby to receive charging current therefrom, a transmitter circuit connected with the storage battery and actuated thereby and a multi-contact switch forming metallic connections between both circuits and means operated from the exterior of the cabinet for controlling said switch, whereby to put the circuits into and out of operation.
10. In a phonograph, the combination with a cabinet, a record and a reproducing device of a microphone transmitter connected with the reproducer, an amplifying receiver carried within the cabinet and connected electrically with the transmitter, an amplifying horn on the receiver also contained within the cabinet, actuating means for the transmitter and amplifying receiver, comprising a receiving circuit connected with an outside supply circuit, a storage battery within the cabinet and connected with the receiving circuit, whereby to receive charging current therefrom, a transmitter circuit connected with the storage battery and actuated thereby and a multi-contact switch forming metallic connections between both circuits, means operated from the exterior of the cabinet for controlling said switch, whereby to put the circuits into and out of operation, and a signal light within the cabinet and visible from without, connected with the switch and the supply

circuit for indicating the charging of the storage battery and the condition of the circuit connections.

11. In a phonograph the combination of 5 a sound box, a microphone transmitter in communication with the sound box, a sound amplifying receiver connected with the transmitter, a horn attached to the amplifier, a rheostat for varying the strength of 10 current in the transmitter circuit, to thereby modulate the volume of sound; a storage battery for supplying current to the transmitter circuit; a dynamo circuit for current to energize the magnetic field of the 15 amplifying receiver and recharge the storage battery and switch mechanism to control the circuits by one operation.

12. In a phonograph, the combination with a cabinet, a record and a reproducing 20 device, of a transmitter connected with the reproducer, an amplifying receiver carried within the cabinet and connected with the transmitter, an amplifying horn on the re-

ceiver also contained within the cabinet, actuating means for the transmitter and amplifying receiver, comprising a storage battery within the cabinet, a transmitter circuit including the primary of an induction coil connected to said storage battery, a secondary for said induction coil, said secondary being connected to the actuating coil of 25 said receiver, a signal circuit including a lamp, said circuits all being contained within the cabinet and one of them being connected to a multi-point switch, said switch 30 being operable from without the cabinet, and a window in the cabinet through which the signal lamp may be viewed.

In testimony whereof we have hereunto set our hands in the presence of two sub- 35 scribing witnesses.

EDWIN STEWART PRIDHAM.
PETER LAURITS JENSEN.
